UNITED STATES PATENT OFFICE

EDWIN ALBJERG, OF FERGUS FALLS, MINNESOTA

AUTOMATIC STORM SASH ADJUSTER

Application filed September 21, 1931. Serial No. 564,179.

This invention aims to provide a means whereby, when a sash is raised and lowered, a storm window may be opened and closed, it being possible, nevertheless, to open the window a little, without opening the closure and it being possible to fold the actuating rod down flat on the closure, to save space, and to avoid damage to the rod, when the closure is taken off the window frame and stacked up in the summer time.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:—

Figure 1 shows in vertical section, a window equipped with the device forming the subject matter of this application;

Figure 2 is a vertical section wherein the window sashes appear in elevation;

Figure 3 is a fragmental horizontal elevation on the line 3—3 of Figure 1;

Figure 4 is a fragmental horizontal section on the line 4—4 of Figure 1;

Figure 5 is an elevation showing the rod folded against the closure;

Figure 6 is a vertical section showing a different way of using the rod.

The numeral 1 marks a window frame. An upper sash 2 is vertically slidable in the window frame 1 and includes a bottom rail 3. A lower sash 4 is vertically slidable in the window frame 1. The numeral 5 marks a closure, such as a storm window, hinged at its upper end to the window frame 1, to swing vertically. The hinge for the storm window 5 is designated by the numeral 6.

Vertical bearings 7 are secured by screws 27, or otherwise, to the sides of the closure 5 and are located near to the bottom rail 3

of the upper sash 2. Horizontal bearings 8 are provided, and have feet 9 at their ends, the feet of the horizontal bearings 8 being attached by screws 10, or otherwise, to the sides of the closure 5. The horizontal bearings 8 are located considerably below the vertical bearings 7. Horizontal arms 11 are overlapped on the upper feet 9 of the horizontal bearings 8 and are held in place by the uppermost screws 10, the lower edges of the arms 11 engaging the bearings 8, so that the arms can not move from the horizontal position shown in Figure 5. At their outer ends, the horizontal arms 11 have vertical tubular guides 12, in which latches 14 are vertically slid able, the latches having heads at their ends, so that the latches can not be disengaged from the guides 12, either upwardly or downwardly. Horizontal keepers 16 are attached in any suitable way, as shown at 17, to the bottom rail 3 of the upper sash 2 and project forwardly with respect to the said rail, as shown in Figure 1 of the drawings. At their inner ends, the keepers 16 have angularly disposed flanges 26, the purpose of which will be made manifest hereinafter. In the edges of the projecting ends of the keepers 16, there are openings or notches 18.

Rods 19 extend lengthwise of the closure 5. Each rod, adjacent to its upper end, has a straight part 20 which is disposed parallel to the closure 5. The straight part 20 of the rod is connected to an off set crank 21, mounted to turn in the bearing 7, and provided at its upper end with a laterally projecting finger 22 which keeps the rod in the bearing 7, when the rod is in the hanging position shown in Figure 5 of the drawings. The lower end of the straight part 20 of the rod is adjoined to an inclined part 23, disposed at an acute angle to the closure 5. On the lower end of the inclined part 23 of the rod there is an outwardly extended arm 24, terminating in a lateral finger 25 received in the horizontal bearing 8, and held therein by the latch pin 14, when the latch pin is in the position shown in Figure 5.

The rod 19, and, more specifically, the parts 23 and 20 of the rod, are received slidably in the notch 18 of the keeper 16 on the

bottom rail 3 of the upper sash 2. When the straight part 20 of the rod is in the notch 18, as shown in Figure 1, the storm closure 5 is held in closed position. It is possible 5 to slide the upper sash 2 downwardly a little way, the keeper 17 riding on the straight part 20, without opening the closure 5. Under such circumstances, whatever air may 10 leak in around the closed window 5, and affords some ventilation, in extremely cold weather. When the upper sash 2 is slid downwardly far enough so that the keeper 16 is 15 on the inclined part 23 of the rod 19, the closure 5 will be swung to open position, on its hinges 6, and the further that the sash 2 is slid downwardly, the more the closure 5 will be opened, until the outer end of the keeper 16 ultimately comes into contact with the arm 24.

20 The finger 25, being received in the bearing 8, holds the rod 19 in the position shown in Figure 1, with the parts 20 and 23 of the rod in a plane at right angles to the closure 5, so that when the upper sash 2 is lowered, 25 the closure will be opened, the closure being closed, as the upper sash is raised.

When it is desired to take off the closure 5 and stow it away, in the summer time, the latch pins 14 are pulled up from the position 30 of Figure 5, out of engagement with the inner ends of the fingers 25, and out of the position of Figure 2. This sets the lower ends of the rods 19 free. The upper ends of the rods fit 35 loosely enough in the vertical upper bearings 7, so that the rods can have a little swinging movement in the said bearings. The lower ends of the rods are swung laterally in Figure 2, to disengage the fingers 25 from the horizontal bearings 8, and, then, the rods are 40 swung in an opposite direction, to get them out of the notches 18 in the keepers 16. Thus, the rods 19 are freed from the keepers 16, without the use of tools. The rods 19 finally 45 may be turned about an axis in the upper bearings 7, so that the rods lie flat against the closure 5, as in Figure 5, and one closure can be stacked up on another, space being economized, and there being no chance of bending the rods out of shape.

50 In Figure 6, parts hereinbefore described have been designated by numerals previously used, with the suffix "a". The rod is turned upside down, the bearings 7a and 8a are 55 shifted accordingly, and the keeper 16a is fastened on the base of the lower sash 4a by securing elements 27, extended through the flange 26a of the keeper, the closure 5a being operated by the lower sash, instead of by the 60 upper sash.

The closure 5 may be connected to the frame 1, near to the lower end of the closure, by pull springs 50 which prevent the closure from rattling whether that member be open or 65 closed.

Having thus described the invention, what is claimed is:—

1. In a device for use in connection with a frame, a sash slideable in the frame, and a closure hinged to the top of the frame: a vertical bearing, means for securing the vertical bearing to the closure, a horizontal bearing, means for securing the horizontal bearing to the closure, a rod extended lengthwise of the closure, the rod comprising an inclined part disposed at an acute angle to the closure in a plane at right angles to the closure, an arm on one end of the inclined part and extended toward the closure, and a rectangular finger on the arm, at one end of the rod, the finger being received in the horizontal bearing, the opposite end of the rod being received in the vertical bearing, a keeper having an opening receiving the inclined part of the rod slidably, to open the closure when the sash is slid in the frame, means for securing the keeper to the sash, and mechanism for holding the finger in the horizontal bearing, to keep the inclined part of the rod in said plane, at right angles to the closure, said mechanism being movable to permit the finger to be withdrawn from the horizontal bearing, the rod having play enough in the vertical bearing to permit the finger to be withdrawn from the horizontal bearing, and to permit the rod to be swung of the opening in the keeper, and the rod being rotatable in the vertical bearing, to enable the inclined portion and the arm to lie flat against the closure when the closure is detached from the frame, and stacked.

2. The device of claim 1, further characterized by the fact that said mechanism embodies a latch slideable on the horizontal bearing, and engaging the rod adjacent to the inner end of the finger.

In testimony that I claim the foregoing as my own, I have hereto affixed my signature.

EDWIN ALBJERG.
